UNITED STATES PATENT OFFICE

2,428,193

MAGNETRON

John P. Blewett, Schenectady, N. Y., assignor to
 General Electric Company, a corporation of
 New York

Application September 23, 1944, Serial No. 555,497

2 Claims. (Cl. 315—39)

1

My invention relates to electric discharge devices, and more particularly to improved electron discharge devices of the magnetron type.

Numerous magnetron constructions employing an array of anode elements about a centrally located cathode, have been employed as high frequency oscillation generators. In accordance with the teachings of the present invention, I provide an improved magnetron construction of this general type which offers numerous advantages from the standpoint of manufacture, adjustment of the frequency of oscillation, cooling of the electrodes, and maximum power output.

It is an object of my invention to provide a new and improved electric discharge device of the magnetron type.

It is another object of my invention to provide a new and improved anode structure and associated high frequency conductors which facilitates manufacture of the magnetron.

It is a still further object of my invention to provide a new and improved magnetron construction which provides a simple structure for the fluid cooling of the anode elements and permits operation of the tube at high power outputs.

In one illustrated embodiment of my invention, the anode structure includes a pair of anode elements having generally semi-cylindrical surfaces arranged on opposite sides of an elongated cathode member to define a substantially cylindrical or annular inter-electrode space. The anode members have their opposed ends spaced to provide gaps. The electrode assembly of which the anode members are a part includes a generally U-shaped structure of hollow tubing, preferably of good conducting material such as copper. The U-shaped assembly is mounted within a dielectric envelope with the parallel arms extending through one end of the envelope and providing connections for a high frequency transmission line. The closed portion of the U-shaped structure extends within the envelope and provides a transmission line section which cooperates with the exterior transmission line to determine the operating frequency of the device.

For a better understanding of my invention, reference may be had to the following description taken in connection with the accompanying drawings and its scope will be pointed out in the appended claims. In the drawings Fig. 1 is a perspective view of one embodiment of my invention; Fig. 2 is an elevational view of a portion of the embodiment illustrated in Fig. 1; Fig. 3 is an elevational view, partially in section, of a modified form of my invention, and Fig. 4 is a plan

2

view in section of the embodiment illustrated in Fig. 3.

Referring now to Fig. 1 of the drawings, I have shown my invention embodied in a magnetron device including an elongated glass envelope 1 of generally cylindrical form. The envelope encloses an anode structure comprising two anode members 2 and 3 having semi-cylindrical faces arranged in opposed relation to provide a circular array. As illustrated in the drawings, the members 2 and 3 are mounted in mutually spaced relation to provide gaps 4 and 5 between them and are respectively supported by parallel conductors 6 and 7 which extend through one end of the envelope and are sealed thereto in any suitable manner. A generally U-shaped loop conductor 8, lying within the envelope, interconnects the anode members 2 and 3. The conductors 6, 7 and 8 are preferably of hollow conducting tubing so that in addition to providing high frequency connections with the anode members 2 and 3 they provide a closed circuit for the flow of cooling fluid. To this end, suitable passages (not shown) are provided through anode members 2 and 3 and the ends of conductors 6, 7 and 8 are positioned in these passages and secured in vacuum-tight relation with respect to the anode members in any suitable manner, as by silver soldering.

30 A source of electrons in the generally annular space defined by the members 2 and 3 is provided by an elongated cathode 9 which may be a tungsten wire, either uncoated or coated with a suitable oxide. The cathode is supported symmetrically between the curved surfaces of the anode members 2 and 3 by lead-in conductors 10 and 11 which are sealed through the base of envelope 1 to provide externally accessible terminals for a source of heating current. One of the terminals may also be connected to a source of high negative direct current voltage if the anode is to be operated at ground potential. It is preferable to provide a spring mounting for the cathode such as provided by the spring arm 45 12 supported by conductor 10 as shown in Fig. 2. Suitable end plates or shields 13, supported from conductor 11 by a wire bracket 14, are provided to minimize the escape of electrons from the inter-electrode space.

50 In Fig. 1 is shown a magnetron device embodying the present invention supported on a metallic shielding enclosure 15 of generally rectangular shape. The top and front sides of the enclosure have been removed to show the high frequency conductors and tuning arrangement

associated with the anode conductors 6 and 7. As illustrated in Fig. 1, the output circuit of the device includes tubular conductors 16 and 17 which form extensions of conductors 6 and 7. The conductors 16 and 17 are of larger internal diameter than conductors 6 and 7 and are provided with resilient end portions 18 which engage enlarged shoulders or terminals 19 provided on the conductors 6 and 7 in the region where those conductors are sealed through the envelope. A 10 funnel-like adapter 20 is provided on the interior of each of the conductors 16 and 17 and together with the resilient sleeve 21 provides means for making a detachable fluid-tight connection between conductors 16 and 17 and 6 and 7, respectively. In this manner cooling fluid, such as air, oil or water, may be circulated from one conductor 16 through conductors 6, 7 and 8 and the anode members 2 and 3 to the other conductor 17.

The operating frequency of the magnetron device is determined by the electrical characteristics of the anode circuit including the anode members 2 and 3, loop conductors 6, 7 and 8 and the effective length of conductors 16 and 17. Provision is made for adjusting the operating frequency of the device by an adjustable metallic plate 22 which is shaped to engage the inner walls of the shielding enclosure 15 and conductively to engage both of the conductors 16 and 17. The position of the member 22 is adjusted by moving the operating rod 22' with any suitable adjusting mechanism (not shown). As illustrated in the drawings, the edges of the member 22 are provided with resilient fingers 23 which engage the wall of the shielding enclosure. It will be understood that similar resilient fingers may be provided to engage the conductors 16 and 17. High frequency energy may be delivered to an output circuit in any suitable manner and in the arrangement illustrated in Fig. 1 a suitable conductive connection including contact 24 is provided. This contact is mounted in insulated relation with respect to the shielding enclosure 15 by means including a fastening element 25 and a pair of insulating washers 26. The conductor 24 is arranged to slide in a slot 27 provided in one wall of the enclosure 15. If desired, movement of the contact 24 may be accomplished by coupling to the mechanism for moving the contacting member 22. Contact 24 may be connected to the central conductor of a concentric output transmission line (not shown).

As is well understood by those skilled in the art, in magnetron devices of the type described above it is necessary to produce a magnetic field in the inter-electrode space which is substantially parallel to the elongated cathode member. In Fig. 2 there is illustrated schematically a pair of pole pieces 28 of an electromagnet (not shown).

The general principles of operation of magnetron devices of the type described above in connection with Figs. 1 and 2 is believed to be well understood by those skilled in the art. With a suitable unidirectional voltage impressed between the anode members and cathode and with a suitable magnetic field established in the inter-electrode space, electrons emitted by cathode 9 move in the inter-electrode space in curvilinear paths due to the resultant action of the electric and magnetic fields and excite the anode structure at a frequency determined by the geometry of the anode structure and the circuits associated therewith. With the particular arrangement illustrated, the frequency of the oscillations

produced is determined by the internal loop 8 of fixed dimensions and the external loop of adjustable dimensions including the effective portion of conductors 16 and 17 determined by the 5 position of the movable member 22. This arrangement including the internal hollow loop provides a magnetron which is easily constructed, readily tuned and which is also easily cooled by circulating a cooling fluid through the system of anode conductors.

The modification illustrated in Figs. 3 and 4 is similar in many respects to the modification of Figs. 1 and 2 and is particularly adapted for high power continuous wave operation. Referring now to Fig. 3, the magnetron device there illustrated comprises a metallic envelope 29 of generally cylindrical shape having a cover member 30 provided with an integral upstanding flange 31 for the purpose of supporting a cathode assembly. The cathode assembly, as illustrated, includes a spool-like cathode member 32 preferably formed of a material such as beryllium copper coated with a good secondary emitter such as magnesium or Dow metal. The cathode member 32 is provided with a recess 33 which houses a small filamentary cathode 34 for providing a source of primary electrons. The filamentary cathode 34 has one terminal thereof connected with the cathode member 32 and the other terminal connected with an externally accessible insulated conductor 35. The entire cathode assembly is supported from the flange 31 in insulated relation with respect to the envelope 29 by a tubular member of conducting material 35 which extends upwardly through the flange 31 and is secured to a suitable metallic sleeve 36 which is, in turn, supported in insulated relation with respect to flange 31 by a glass sleeve 37. The cathode assembly may be made removable and be held in position within the sleeves 31 and 36 by a closure member 38 which is threaded, or otherwise secured, to the upper end of the sleeve 36. Suitable pipes 39 and 40 may be provided in the cathode assembly for supplying cooling fluid to the interior of the main cathode body 32. The cathode structure described above is claimed and more fully described in the copending Blewett and Langmuir application, Serial No. 555,496, filed concurrently herewith and assigned to the assignee of the present application.

The anode structure of the modification shown in Figs. 3 and 4 is in general similar to that shown in Figs. 1 and 2 and comprises a pair of anode members 41 and 42 which are arranged on opposite sides of the cathode member 32 and shaped to provide a generally annular inter-electrode space. The members 41 and 42 are mutually spaced to provide gaps 43 and 44. Hollow tubular conductors 45, 46, and 47, 48 are connected with the opposite ends of anode members 41 and 42 and extend through the side wall of the container 29 to support the anode members 41 and 42. Conductors 45 and 47 are preferably joined on the exterior of the container 29 by a fitting 65 49 to complete a circuit for the flow of cooling fluid from conductor 46 to conductor 48. When employing a metallic container, such as illustrated by container 29, the effective length of the loop including conductors 45 and 46 is determined by the wall of container 29 rather than by the end of the loop provided by member 49. In the arrangement illustrated a conducting member 50 is arranged to engage the conductor 46 and to be moved along the length of these 70 conductors by a suitable adjusting screw 51 to

adjust the operating frequency of the device. The mechanical connection between the operating screw 51 and the conductor 50 may be made through the housing in any suitable manner, and preferably is made through a bellows 52 to permit movement of the member 50 while the container 29 remains adequately sealed. High frequency energy may be extracted from the anode system of the device in any suitable manner. As illustrated in Fig. 4 of the drawings, the internal conductor 53 of a concentric-type transmission line is conductively connected with the conductor 45. The conductor 53 is preferably hollow and connected into the hollow conductor 45 so that cooling fluid may be circulated through the conductor 53 by the same cooling system as employed for the remainder of the device. The conductor 53 is supported in insulated relation with respect to the container 29 and the outer conductor 54 of the output transmission line by an insulating disk 55. In Fig. 3 fragmentary portions of the electromagnetic pole pieces have been illustrated at 56.

While I have shown and described a particular embodiment of my invention, it will be obvious to those skilled in the art that changes and modifications may be made without departing from my invention in its broader aspects, and I, therefore, aim in the appended claims to cover all such changes and modifications as fall within the true spirit and scope of my invention.

What I claim as new and desire to secure by Letters Patent of the United States, is:

1. A magnetron device including an hermetically sealed envelope, a structure for generating oscillations comprising a U-shaped conductive member of hollow tubing having a U-shaped end thereof within said envelope and parallel arms thereof extending through a wall of said envelope, said arms constituting a high frequency transmission line and said U-shaped end constituting a section determining the operating frequency of said structure, a conductor exterior of said envelope connecting said arms further determining the operating frequency of said structure, a pair of anode members within said envelope each supported by one of said arms intermediate said

5 U-shaped end and said exterior conductor, said anode members having opposed curved surfaces defining a substantially cylindrical space, and a cathode within said space for supplying electrons thereto.

2. A magnetron device including an hermetically sealed envelope, a structure for generating oscillations comprising a U-shaped conductive member of hollow tubing adapted to close a circuit for the flow of cooling fluid and having a U-shaped end thereof within said envelope and parallel arms thereof extending through a wall of said envelope, said arms constituting a high frequency transmission line and said U-shaped end constituting a section determining the operating frequency of said structure, a conductor exterior of said envelope connecting said arms and adjustably positionable longitudinally thereof for further determining the operating frequency of said structure, a pair of anode members within said envelope each supported by one of said arms intermediate said U-shaped end and said exterior conductor, said anode members having opposed curved surfaces defining a cylindrical space charge chamber, and a cathode coaxially mounted within said chamber for supplying electrons thereto.

JOHN P. BLEWETT.
